UNITED STATES PATENT OFFICE

JOHN E. PERRY, OF SHARON, PENNSYLVANIA, ASSIGNOR TO VALLEY MOULD AND IRON CORPORATION, OF SHARPSVILLE, PENNSYLVANIA, A CORPORATION OF NEW YORK

INGOT MOLD WITH CHILLED MATRIX WALLS AND APPARATUS FOR MAKING SAME

Application filed July 3, 1926. Serial No. 120,280.

This invention relates broadly to metallurgy and more specifically to the manufacture of ingot molds and the like.

Heretofore in the art, it has been customary in the casting of ingot molds to utilize cores comprising a core bar covered with a thick layer of mold sand. This sand formed the core surface and would crumble when the core bar was stripped from the solidified mold, thereby relieving the stress and strain on the mold during the stripping operation. These sand walls of the core, having a relatively low rate of heat conductivity, tended to retain the inner or matrix walls of the ingot mold cast in such set-up in a non-chilled condition so that the inner or matrix faces of the ingot mold walls comprised relatively open grained cast iron. This inner wall, due to the sand on the core, was always more or less roughened, and being of soft open grained metal, tended to cut away relatively rapidly when subjected to or struck by a flowing stream of molten steel.

The present invention overcomes the difficulties of the known art by providing a metal core having metal faces adapted to be brought directly into contact with the molten iron when the ingot mold is being cast. These metal faces of the core being good conductors of heat, rapidly chill the molten iron adjacent the core and thereby produce chilled metal faces on the matrix portion of the ingot mold cast in this new set-up. Such an ingot mold cast against a cold metal core has fine grained metal adjacent the matrix surface which is very smooth and hard because of having been cast against a smooth metal chill surface. The graphitic carbon in the molten iron adjacent the cold metal core tends to assume nodular or spherical forms while the molten iron is freezing. This is one factor in producing the fine close grain in the solidified metal, which is very resistant to erosion from the hot stream of molten steel while an ingot is being poured, and which also tends to delay fire cracking of the ingot mold due to successive heats while in use.

The preferred form of core, according to the present invention, comprises a core member formed of a plurality of metal side plates

constructed in such manner as to be collapsible, and thereby occupy a lesser space when collapsed than when full open, so that the collapsed core member may be easily withdrawn after the mold is cast. Furthermore, the joints between the plates on said core are arranged on the side faces in such manner as to comprise straight longitudinal lines, so that any slight ridge left by said joints on the matrix face of the ingot mold will produce a very slight groove on the ingot, which does not interfere in any way with stripping operations or with the fabrication of the ingot. The movable side plates of the core are controlled in such manner that certain of the side plates initially move inwardly, while others of the side plates are held stationary in order to permit the edges of the moving plates to pass the edges of the initially stationary plates to provide clearance for the inward movement of all said side plates as the core is collapsed.

It is realized that the present invention may be embodied in constructions other than those herewith specifically disclosed. Therefore, it is desired that this disclosure be considered as illustrative and not in the limiting sense.

Fig. 1 is an elevational view of a set-up for casting ingot molds in accordance with the present invention and illustrating a portion of the set-up in section.

Fig. 2 is an elevational sectional view through an ingot mold cast in accordance with the present invention.

Fig. 3 is an elevational sectional view through a collapsible core in accordance with the present invention and taken on the line 3-3 of Fig. 5.

Fig. 4 is an elevational sectional view of a core in accordance with the present invention taken on line 4-4 of Fig. 5.

Fig. 5 is a sectional view taken on line 5-5 of Fig. 3.

Fig. 6 is a view similar to Fig. 5 but showing the relation of the plates when the core is collapsed.

Referring now to the drawings and more particularly to Fig. 1, the flask 1 is set in the usual manner upon a base plate 2, and the

flask carries the usual side wall 3 of rammed sand. The base plate preferably is recessed to receive the bottom 4 of the metal core 5 in such manner that the side plates of the metal core rest on the face of the base plate and form a metal to metal joint at this juncture. However, the bottom of the matrix 6 of the set-up may be sand faced where it is not desired to chill the bottom portion of the ingot mold.

10 Referring now more particularly to Fig. 3, the core preferably is of the collapsible type and therefore is composed of side plates and a control mechanism for causing the side plates to have a movement towards and away from the axis of the core. In the preferred form illustrated, the core member is provided with a bottom 4 which carries a vertical standard or support comprising a tube 7.

15 The tube 7 surrounds a slidable control bar 8, which carries pairs of control plates 9 and 10 arranged at substantially right angles to each other, since the core is substantially rectangular in cross section. These control plates extend through slotted openings 11 and 12 in the tube 7. The control plates 9 are provided with full inclined cam slots 14 that enclose rivets 15 extending between the arms 16 which are integral with the side plates 17. Preferably, the side plates 17 are recessed as at 18 to form clearance spaces for the ends of the control plates 9. From the construction just described, it will appear that if the parts are in position shown in 20 Figure 3 and the control bar 8 be forced downwardly, the action of the cam slots 14 on the rivets 15 will cause the side plates 17 to move inwardly toward the axis of the control bar.

25 Referring now to Fig. 4, it will be observed that the control plates 10 are provided with double cam slots having a vertical portion 19 and a short inclined portion 20. Also, that these slots cooperate with rivets 21 extending between the arms 22 carried by the side plates 24, and that the side plates 24 are recessed at 25 to form clearance spaces for the ends of the control plates 10. Assuming the parts to be in the position shown in Fig. 4 and that the control bar 8 be forced downwardly, it will be observed that so long as the rivets 21 are in the vertical portions 19 of the cam slots, that the side plates 24 will be stationary, but that as soon as the rivets 21 encounter the inclined portions 20 of the cam slots, the side plates 24 will move inwardly.

30 Considering Figs. 3, 4, 5, and 6, it will be observed that with the parts in positions shown in positions 3, 4, and 5, and the control bar 8 then forced downwardly, the side plates 17 will move inwardly until the edges of the side plates 17 clear the edges of the side plates 24. At this time the rivets 21 will 35 encounter the short inclined portion 20 of

the control plates 10 and now the side plates 24 will start to and continue to move inwardly coincident with the continued inward movement of the side plates 17, until in their final innermost position, the plates 70 will occupy the relation illustrated in Fig. 6. The expanded periphery of the core is indicated in Fig. 6 by the dotted line 26, and it will be observed that the side plates, when collapsed, are well within the lines represented by the dotted line 26 so that the core can easily be removed from the solidified ingot mold.

75 The bottoms 27 of the side plates are preferably machined to form a metal to metal joint with the base plate 2 when the core is in position in the set-up, although where desired a sand floor may be provided on the base plate.

80 The side plates 17 and 24 may comprise any suitable chill material, but preferably comprise cast iron; and the outer faces of these side plates are preferably smooth so that when the core is expanded, a very smooth continuous periphery of the shape desired is provided so that a smooth matrix is formed on the ingot mold cast within this set-up. Preferably, sufficient weight of metal is provided in the side plates of the core member to effectually chill the hot molten iron cast 90 against these side plates. The thickness of metal in these side plates prevents burning out of the side plates and produces the desired chill on the ingot mold cast against these chilling members.

100 Preferably, the top of the core member is covered by a top plate 28, and the control bar 8 may be slotted to receive a key 29 which bears on the top plate 28 to retain the core in expanded relation. The key 29 is driven out when it is desired to collapse the core.

An ingot mold cast in accordance with the present invention comprises cast iron side walls A and a matrix B, with the metal at C, comprising the surface of the matrix walls, and also the metal adjacent thereto being chilled. This chilling of the metal at C produces a close fine grained structure with the graphitic carbon in nodular or spherical form and with the surface of the matrix wall extremely smooth and dense, while the remaining portion of the side walls of the ingot mold are of a softer more open crystalline structure of a less friable nature than the chilled portion. The hard chilled surface resists erosion from the hot steel poured in the mold and also resists fire cracking while the condition of the metal in the body of the side wall produces strength and elasticity required in ingot molds.

110 The molten iron used for casting the ingot mold comprising the present invention may be suitable iron adaptable for this purpose, but preferably comprises molten iron direct from the blast furnace. Such molten iron is 120

known as "direct metal" and the uncombined iron in "direct metal" carries a large content of free or graphitic carbon as well as some iron carbides, all of which is mixed in the molten mass. As such a mass freezes the metal tends to throw out the free carbon as graphite flakes; but where such metal is chilled rapidly while freezing the character of the frozen mass adjacent the chill is changed to a dense close grain with the free or graphitic carbon in nodular or spherical form, interspersed with uncombined iron and an increased amount of combined iron and carbon, or iron carbide. The frozen mass remote from the chilled portion is of a more open crystalline structure containing free or graphitic carbon in flake form and a lesser amount of iron carbide and a larger amount of uncombined iron. The chilled portion is hard and brittle and this dense crystalline structure blends into a softer tougher and more malleable unchilled metal comprising the supporting cast iron body of the ingot mold.

Having thus described my invention, what I claim is:

1. An article of manufacture comprising an ingot mold cast from direct metal with a large content of free carbon and having the metal adjacent the surfaces comprising the matrix of the mold chilled to substantially a uniform depth over a portion of the matrix of the mold and with the outer portions of the ingot mold walls comprising unchilled cast iron.

2. An article of manufacture comprising an ingot mold of cast iron with the graphitic carbon in the cast iron adjacent the matrix face of the mold being in nodular form and with the outer portions of the ingot mold walls comprising cast iron with the graphitic carbon therein in flake form.

3. An article of manufacture comprising an ingot mold of cast iron cast from direct metal with a large content of graphitic carbon contained therein with the graphitic carbon in the cast iron adjacent the matrix face of the mold being in nodular form and with the outer portions of the ingot mold walls comprising cast iron with the graphitic carbon therein in flake form.

4. A set-up for casting an ingot mold comprising in combination a sand mold for the outer portions of said ingot mold, and a chill core to form the matrix of said ingot mold.

5. A set-up for casting ingot molds comprising in combination a flask carrying a sand wall to determine the exterior shape of the ingot mold, and a collapsible chill core forming the matrix of said ingot mold.

6. A set-up for casting ingot molds, said set-up comprising in combination, a bottom plate, a flask having sand side walls set on said bottom plate, and a chill core forming a metal joint with said bottom plate and being

adapted to form the matrix of said ingot mold.

7. The method of casting ingot molds which comprises chilling the matrix side of the mold walls during casting and maintaining the outer side of said mold walls unchilled.

8. The method of casting ingot molds from direct metal containing a large content of free carbon which comprises chilling the hot metal adjacent the matrix side of the mold walls during casting and maintaining the hot metal adjacent the outer side of said mold walls unchilled.

9. The method of casting ingot molds comprising chilling the matrix side of the walls of the ingot molds throughout their length during the casting operation while maintaining the remaining portion of the ingot mold unchilled.

10. The method of casting ingot molds from direct metal comprising chilling the matrix side of the walls of the ingot molds to a uniform depth throughout their length during the casting operation while maintaining the remaining portion of the ingot mold unchilled.
